UNITED STATES PATENT OFFICE.

ALEX KORBA, OF HOUSTON, PENNSYLVANIA.

RAIL CHAIR.

Application filed April 11, 1923. Serial No. 631,401.

To all whom it may concern:

Be it known that I, ALEX KORBA, a citizen of the United States, residing at Houston, in the county of Washington and State of Pennsylvania, have invented certain new and useful Improvements in Rail Chairs, of which the following is a specification, reference being had to the accompanying drawings.

10 This invention relates to means for holding railroad rails upon ties, and particularly to rail chairs for this purpose.

The general object of the invention is to provide a rail chair having means thereon which automatically engage the base flange of the rails at the joint between two rails and hold the rails firmly to this chair or bed plate against lateral thrust or tipping thrust, but the construction being such as will permit 20 the relatively easy detachment of the rails from the chair whenever it is necessary to replace the rails.

A further object is to provide a device of this character having means whereby the 25 chair is braced from the adjacent rail so as to hold the rails which rest upon the chair and the adjacent rail at proper gauge or distance from each other.

A still further object is to provide the last 30 named rail spacing means with means for gripping the last named rail which is released when the first named rails are lifted from the chair.

Another object is to provide a chair of 35 this character with rail engaging means comprising hook-like members pivoted upon the chair, each hook-like member having a tail extending beneath the corresponding rail and upon which the rail rests, the weight of 40 the rail and the weight of the train passing over the rail acting to depress the tail of the rail engaging members and causing the hook-like end thereof to engage firmly over the flange of the rail so that the rail cannot 45 lift up while a train is upon the rail and cannot ordinarily be lifted or detached from the chair except by manually lifting the rail vertically upward.

Other objects have to do with the details 50 of construction and arrangement of parts as will appear more fully hereinafter.

My invention is illustrated in the accompanying drawings, wherein:

Figure 1 is a top plan view of a rail chair 55 constructed in accordance with my invention and showing it applied;

Figure 2 is a section on the line 2—2 of Figure 1;

Figure 3 is a section on the line 3—3 of Figure 1;

Figure 4 is a section on the same plane as Figure 3, but showing the latches in a retracted position;

Figure 5 is a section on the line 5—5 of Figure 3;

Figure 6 is a section on the line 6—6 of Figure 1.

Referring to these drawings, 10 designates the body of a chair which is in the form of a plate and adapted to extend from one tie 70 A to a next adjacent tie and beneath the joint between two rails B. These rails B are shown as having the usual angular fish plates C. The base plate 10 or chair is preferably formed with a pair of parallel, 75 longitudinally extending, upwardly projecting ribs 11 which are spaced apart so as to snugly receive the base of the rail between them and tend to prevent any lateral movement of the rail. The lateral margins of the 80 plate are flanged at 12 and provided with screws 13 whereby the locks or latches may be held in firm engagement with the rails against accidental displacement.

The plate is formed with a plurality as, 85 for instance, four transversely extending slots 14. I have illustrated four of these slots but more slots may be used. There are an even number of these slots 14 and the slots are disposed in staggered relation to 90 each other. The under face of the chair is provided on each side of these slots with depending ears 15, and disposed in each slot is a rail engaging member or latch 16. This has the form of a lever having a depending 95 ear 17 which extends downward between the ears 15 and is pivoted thereto by a transverse bolt 18. One end of each latch is formed with an inwardly and upwardly extending hook 19 and the latch is extended 100 beyond its pivotal axis to form a tail 20. The upper faces of these tails are upwardly beveled, as will be seen from Figure 4. Thus it will be obvious that when a rail is laid upon the chair 10 between the flanges 11, the base of the rail may rest upon these upper faces of the locking levers 16 and engaging against the tails will force the tails of the levers downward, causing the hooked 105 ends of the levers to be projected over the edge of the rail and over the margins of the fish plate, if fish plates are used. The

extreme end of the tail is formed with a stop lug 21 which prevents the tail of the fastening device from being lifted too high and the hook-shaped portion being depressed to too great an extent.

It will be seen that with this construction when a rail is laid upon the upper faces of the lever-like fastening devices they will depress the tails of these fastening devices, causing the hooks to extend over the flanges of the rail and thus lock each rail against accidental upward movement. When the weight of a train is upon the rails B, the tails of the locking levers will be depressed with so much force that it will be impossible for the rail to leave the fish plate and the rail will be locked securely thereon both against lateral movement, against tipping thrust and against upward movement. This is additionally prevented by the screws 18 which pass through the flanges 12 of the chair and engage against the ends of the latches, holding these latches raised. Obviously when the screws are removed the latches may be depressed by first elevating the rail.

In order to space the two rails of the track from each other and hold these rails properly spaced and at the proper gauge, I provide a spacing means which comprises a bar 22 which is forked at one end to embrace the base plate or chair 10 and is bolted or riveted thereto, as at 23. This bar at its end remote from the bifurcated portion is hooked, as at 24, to extend over the outer base flange of the rail and the bar is slotted at 25, and disposed within this slot is a rail lock or fastener 26. This has a depending lug 27 through which passes a pin 28 which extends into the bar 22 to thus lock the fastener in its rail clamping position. This lock extends over the flange, as at 29, and the lock is pivoted at 26^a to the bar 22, the lock extending downward through the slot 25. Pivoted to this extremity 30 is a longitudinally reciprocatable rod 31 held to the rod 30 by a rivet, bolt or other suitable means. The other end of this rod is bifurcated and engaged with a bell crank lever 32 having trunnions 33 intermediate its ends. The end of the lever 32 which is remote from the bar 22 extends downward and laterally and the forked end of the rod 31 is pivoted to this extension 34 by a rivet, bolt or other suitable means. The body of this lever 32 is disposed within a slot 35 formed in the bed plate or chair 10 preferably midway of the width of the chair so that the whole weight of the rail rests upon the body portion of the lever, forcing it downward, thus exerting tension upon the rod 31 which pulls upon the tail 30 and causes the rail engaging extremity to be clamped down upon the base of the rail. Obviously when the rails on the chair are manually lifted

this will relieve strain upon the lever 32 and then the rail engaged by the rail clamp 26 may be readily lifted by shifting the clamp 26 to its released position. This construction spaces one rail of the track from the other rail at the joint of the two rails resting upon the chair 10, thus holding one set of rails in parallel relation to the next adjacent longitudinal line of rails and preventing any tendency of the rails to spread or move independently. Of course, it will be understood that the chairs 10 will be used along the joints of both lines of rail.

It will be seen that the construction which I have described eliminates the necessity for spiking the rails directly to the ties, with all the disadvantages incident to these spikes as, for instance, the spike killing of the ties, rotting of the ties, etc. The ties will last a great deal longer for the reason that the rails will rest at the joints upon the chairs 10, which in turn rest upon two ties. The two rails at the joint will be held much more firmly than by the use of spikes and the rails will be held in absolute alignment with each other. Where spikes are used, there is no means of holding the rails absolutely in alignment as the spikes engaging the end of one rail may shift or be pulled out without affecting the other rail. With my construction, the adjacent ends of both rails are firmly held in alignment and one rail cannot be removed without the other rail moving. The construction clamps the rail firmly to the bed, particularly at the time when the wheels of a train are passing over the joint. The greater the tipping thrust on the rail or strain upon the rail, the greater the holding power of the rail clamping devices.

I claim:

1. A rail chair comprising a base plate adapted to extend longitudinally of the rail, two sets of latches pivoted on the plate and operating through slots therein and having tails extending beneath the rails and forced downward thereby, thus projecting the opposite end of the latches into engagement with the rails, one set of latches being disposed reversely to the other set.

2. A rail chair comprising a base plate, latches pivoted on the plate and operating through slots therein, each latch having at its outer end an inwardly and upwardly projecting hook-shaped portion and on its opposite end being formed to provide a tail upon which the base of the rail is adapted to rest to thus cause the projection of the hooked ends of the latches into engagement with and over the base flange of the rail, one set of latches being disposed reversely to the other set, the base plate being formed upon its upper surface with longitudinally extending ribs spaced apart a distance equal to the width of the rail base.

3. A rail chair comprising a base plate upon which the rail is adapted to rest, latches pivoted on the plate and operating through slots therein, the latches being pivoted intermediate their ends and the outer end of each latch being formed to provide an upwardly and inwardly projecting hook, the latch extending in the other direction beyond said pivot and the upper face of the latch being upwardly beveled away from the hook, the body of the latch normally extending beneath the chair and being engaged thereby to cause the projection of the hooked ends of the latches over the face of the rail, and a spacing bar operatively connected to the chair and extending to a parallel rail and having means for clamping upon the parallel rail.

4. A rail chair of the character described comprising a plate adapted to extend longitudinally of the track and support adjacent ends of a pair of rails at the joint between the rails, the upper face of the chair being provided with longitudinally extending ribs with which the edges of the base flange of the rail engage and the chair having a plurality of transversely extending slots disposed in staggered relation, latches disposed in said slots and operatively pivoted to the chair, each latch being pivoted intermediate its ends and at one end being formed to provide a hook, the opposite end constituting a tail extending beneath the rail and the upper face of the latch being upwardly beveled away from the hook whereby to cause the projection of the hooked ends of the latches over the base of the rail when the rail rests upon the chair, a spacing bar operatively connected to the chair at its middle and extending laterally therefrom and adapted to be disposed beneath the middle of a parallel rail, a rail clamping device on the outer end of the spacing bar, and means for shifting the clamping device into rail engaging position including a bell crank lever operatively pivoted upon the chair, the chair being slotted to accommodate the bell crank lever and the bell crank lever having a downwardly depending arm.

5. A rail chair of the character described comprising a plate adapted to extend longitudinally of the track and support adjacent ends of a pair of rails at the joint between the rails, the upper face of the chair being provided with longitudinally extending ribs with which the edges of the base flange of the rail engage and the chair having a plurality of transversely extending slots disposed in staggered relation, latches disposed in said slots and operatively pivoted to the chair, each latch being pivoted intermediate its ends and at one end being formed to provide a hook, the opposite end constituting a tail extending beneath the rail and the upper face of the latch being upwardly beveled away from the hook whereby to cause the projection of the hooked ends of the latches over the base of the rail when the rail rests upon the chair, a spacing bar operatively connected to the chair at its middle and extending laterally therefrom and adapted to be disposed beneath the middle of a parallel rail, a rail clamping device on the outer end of the spacing bar, and means for shifting the clamping device into rail engaging position including a lever pivoted upon the chair and with which the base of the rail is adapted to engage.

6. The combination with a rail chair having rail clamps thereon, of means for spacing the rails supported by said chair from a parallel rail comprising a spacing bar attached to the rail chair and adapted to extend beneath the other rail and having a hooked extremity, a rail clamping member pivoted to the outer end of said spacing bar and having a downwardly extending tail, a rod pivoted to the tail and extending beneath the chair, and a bell crank lever pivoted on the chair having a downwardly extending arm to which the rod is pivoted, the other arm of the bell crank lever extending beneath the rail and being depressed thereby.

7. A rail chair comprising a base plate adapted to extend longitudinally of the rail, two sets of latches pivoted on the plate and operating through slots therein and having tails extending beneath the rails and forced down thereby, thus projecting the opposite ends of the latches into engagement with the rails, one set of latches being disposed reversely to the other set, and removable stop members inserted through the chair and engaging beneath the latches and holding the hooked ends of the latches from depression.

8. The combination with a rail chair having rail clamps thereon, of means spacing the rails supported by said chair from a parallel rail comprising a spacing bar attached to the rail chair, a rail clamping member pivoted to said spacing bar and adapted to extend over the base of the first named rail and having a downwardly extending tail, a detachable pin locking the rail clamping member in its lowered position against the rail, a rod pivoted to the tail and extending beneath the chair, and means engaged by the rail carried on the chair for holding the rod retracted and the rail clamped in its lowered position.

In testimony whereof I hereunto affix my signature.

ALEX KORBA.
